(57) **CLAIM**

I claim the ornamental design for an eyeglass case, as shown.

DESCRIPTION

FIG. 1 is a front view of the eyeglass case of the present design;

FIG. 2 is a back view thereof;

FIG. 3 is left side view thereof;

FIG. 4 is a top view thereof;

FIG. 5 is a bottom view thereof;

FIG. 6 is a perspective view thereof;

FIG. 7 is a perspective view thereof in separated state; and,
FIG. 8 is an enlarged top view of the body portion of the case.

The portions of inner surfaces that are not shown, as well as those inner portions which are left unshaded, form no part of the claimed design.
